(57) **CLAIM**

The ornamental design for a tube trap with tube trap base combination, as shown and described.

DESCRIPTION

FIG. 1 is a bottom front isometric view of a tube trap portion of a tube trap with tube trap base combination, shown in a disassembled state and showing the design.

FIG. 2 is a bottom rear isometric view thereof.

FIG. 3 is a front elevation view thereof.

FIG. 4 is a rear elevation view thereof.

FIG. 5 is a left elevation view thereof.

FIG. 6 is a right elevation view thereof.

FIG. 7 is a top plan view thereof.

FIG. 8 is a bottom plan view thereof.

FIG. 9 is a bottom front isometric view of a tube trap base portion of a tube trap with tube trap base combination, shown in a disassembled state and showing the design.

FIG. 10 is a bottom rear isometric view thereof.

FIG. 11 is a front elevation view thereof.

FIG. 12 is a rear elevation view thereof.

FIG. 13 is a left elevation view thereof.

FIG. 14 is a right elevation view thereof.

FIG. 15 is a top plan view thereof.

FIG. 16 is a bottom plan view thereof.

FIG. 17 is a bottom front isometric view of the tube trap with tube trap base combination, showing the design.

FIG. 18 is a bottom rear isometric view thereof.

FIG. 19 is a front elevation view thereof.

FIG. 20 is a rear elevation view thereof.

FIG. 21 is a left elevation view thereof.

FIG. 22 is a right elevation view thereof.

FIG. 23 is a top plan view thereof; and,

FIG. 24 is a bottom plan view thereof.

The shading lines shown in the drawings represent the approximate three-dimensional contour of the claimed design and are not intended to indicate surface decoration.

(Continued)

The dashed lines in the drawings illustrate portions of the tube trap with tube trap base combination that form no part of the claimed design.
